DISPLAY STAND

Melvin J. Gordon, Brookline, Mass.

Application September 19, 1950, Serial No. 12,249

Term of patent 14 years

(Cl. D80—9)

To all whom it may concern:

Be it known that I, Melvin J. Gordon, a citizen of the United States, residing at 55 Lee Street, Brookline, Massachusetts, have invented a new, original, and ornamental Design for a Display Stand, of which the following is a specification, reference being had to the accompanying drawing, forming a part hereof, in which the drawing shows a perspective view of my design for a display stand.

The dotted lines are only for illustrative purposes.

I claim:

The ornamental design for a display stand, as shown and described.

MELVIN J. GORDON.
